UNITED STATES PATENT OFFICE.

JOHN B. ANSLEY, OF NEW ORLEANS, LOUISIANA, ASSIGNOR OF ONE-HALF TO FRANCIS B. HULL, OF JACKSON, MISSISSIPPI.

CURB-PROTECTOR.

SPECIFICATION forming part of Letters Patent No. 773,451, dated October 25, 1904.

Application filed December 23, 1903. Serial No. 186,875. (No model.)

To all whom it may concern:

Be it known that I, JOHN B. ANSLEY, a citizen of the United States, residing at New Orleans, in the parish of Orleans, State of Louisiana, have invented certain new and useful Improvements in Curb-Protectors, of which the following is a specification, reference being had therein to the accompanying drawings.

This invention relates to a curb-protector or corner-shield, and particularly to means for securing or anchoring the same within a body of concrete or similar material.

The invention has for an object to provide a novel and efficient construction of reversible corner-bar and also a coöperating anchor adapted to receive a tenon formed upon said bar.

Other and further objects and advantages of the invention will be hereinafter set forth and the novel features thereof specifically defined by the appended claims.

In the drawings, Figure 1 is a sectional perspective showing the application of the invention to a curb; Fig. 2, a perspective of the bar, and Fig. 3 a similar view of the anchor for the bar.

Like letters of reference refer to like parts in the several figures of the drawings.

The letter A designates the corner-bar, which may be of any preferred cross-section, but is preferably provided with curved faces A', having converging side walls A² extending inwardly therefrom and joined at their bases to form opposite abutting dovetailed tenons, thus forming a bar similar in construction upon each face in order that it may be reversed in position whenever desired. This bar is held in position by means of an anchor B, having intermediate of its ends a dovetailed mortise B' of suitable configuration to fit the tenon of the bar. This mortise may be provided at any desired point and is here shown as formed within a laterally-projecting portion B², extending from the anchor. The anchor may be also provided at each end with an enlarged head portion B³ for the purpose of retaining the anchor against longitudinal movement within the body of concrete or other similar mate-

rial within which it is embedded. Such a body of embedding material is shown at C in Fig. 1, while a finishing-surface C', of cement or granolithic, is indicated at C'.

In the application of the invention the body of concrete is placed within a mold or form, and while still soft or plastic the bar, with the anchors attached, is embedded within the concrete and forced downward therein to its proper position, the heads upon the anchor serving to contact with the walls of the form to guide and hold it in proper position. When thus inserted, the concrete sets about the bar and anchor and firmly secures it in position, when the finishing-surface may be applied. It will be seen that the dovetailed connection with the anchor prevents any movement of the bar outwardly therefrom or any disengagement by a lateral movement incident to pressure against the bar due to backing a wagon into contact therewith or from any other cause. The heads upon the anchor being disposed flush with the surface of the material also form a protecting-face and effectually prevent any longitudinal movement of the anchor within the concrete. The reversible character of the bar greatly lengthens the life thereof and in the event of injury or a resetting of the curb permits a complete reversal thereof, thus presenting a new wearing-surface and effecting a material saving in the permanent maintenance of the corner-protector. The bar may be formed of any material—for instance, galvanized steel—while the anchor, if desired, may be of cast-iron. The invention has been described as applied to a curb; but it will be obvious that it is applicable to any other position where a corner is to be protected.

It will be seen that changes may be made in the details of construction and configuration without departing from the spirit of the invention as defined by the appended claims.

Having described my invention and set forth its merits, what I claim, and desire to secure by Letters Patent, is—

1. In a curb-protector, a bar extending between the opposite vertical faces of a curb and an anchoring-mortise upon one side thereof

- disposed diagonally to and in the plane of the body of the bar, and a corner-bar provided upon its opposite sides with tenons to fit the mortise, whereby said corner-bar is reversibly disposed at an acute angle to the anchor-bar. 5
2. A corner - bar having a tenon with a curved face and converging side walls, and a support comprising a body having enlarged heads at its opposite ends and an intermediate mortise to receive said tenon. 10
3. In a curb-protector, a horizontally-disposed bar extending between the opposite vertical faces of a curb and having a laterally-disposed anchoring-mortise upon the upper face thereof disposed in the plane of the body of the anchor, and a reversible corner-bar provided with tenons to fit said mortise and supported diagonally above said anchor at the intersection of the front and top surfaces of the curb. 15
4. A corner-bar comprising opposite dovetailed tenons joined at their base and having curved outer faces, and an anchor comprising a body having a lateral extension therefrom provided with a mortise, and dovetailed heads at the opposite ends of said body. 20
5. In a curb-protector, an anchor having a body extending between the opposite vertical faces of the curb, and a corner-bar disposed upon the upper face of said anchor to provide a shield at the intersection of the front and top surfaces of the curb. 30
6. In a curb-protector, an anchor having a body extending between the opposite vertical faces of the curb, and a reversible corner-bar having opposite similar faces, one of which is secured to the upper face of said anchor while the opposite face provides a shield at the corner of the curb. 35
7. In a curb-protector, a support having a body extending between the opposite vertical faces of the curb, and a corner-bar carried by said support to provide a shield at the intersection of the front and top faces of the curb. 40
8. In a curb-protector, a support embedded within a curb composition extending between the opposite vertical faces of the curb and provided with a recess, and a corner-bar having opposite similar faces either of which is adapted to fit said recess. 45

In testimony whereof I affix my signature in presence of two witnesses.

JOHN B. ANSLEY.
